Henry L. Reynolds.
ATTORNEY

UNITED STATES PATENT OFFICE.

ARCHIBALD ROBERTSON, OF SEATTLE, WASHINGTON.

VAPORIZING-PRIMER.

1,318,693.

Specification of Letters Patent. Patented Oct. 14, 1919.

Application filed October 21, 1918. Serial No. 258,977.

To all whom it may concern:

Be it known that I, ARCHIBALD ROBERTSON, a citizen of the United States, and resident of the city of Seattle, county of King, 5 and State of Washington, have invented certain new and useful Improvements in Vaporizing-Primers, of which the following is a specification.

My invention relates to internal combustion engines and consists of a device for supplying aqueous vapor to the charge for such engines and which also may be used as a means for priming the engines.

The object of my invention is to provide 15 a simple device by which a regular supply of aqueous vapor, heated to a considerable temperature, may be supplied in an efficient manner to the charge for such engines, and at the same time to have the device capable 20 of being employed for the purpose of supplying a small amount of gasoline to form priming charges for such an engine.

The accompanying drawings show the invention embodied in constructions which 25 illustrate the principle of my invention.

Figure 1 shows the cylinders of an engine together with the intake manifold, and the manner of applying my invention thereto.

Fig. 2 is a vertical section through the 30 priming cup and its connection with the manifold.

Fig. 3 is a side view, partly in section, showing the same parts but of a different construction, the principle, however, being 35 the same.

It has been found advantageous in the operation of internal combustion engines to provide a certain amount of aqueous vapor to the charge of such engines. This is beneficial in increasing somewhat the power developed by the charge and also in maintaining the cleanly condition of the cylinder and piston, and to prevent the deposit of carbon thereon.

In accordance with my invention I provide means for introducing this aqueous vapor to the intake manifold 1. This is preferably introduced to the manifold at the point where it branches to reach the 50 various cylinders. Fig. 2 shows a preferred construction of this part of the device.

This employs a cup 2 which has a tubular neck 20 extending laterally therefrom and beneath the cup. This cup is in communica-

cation with the conduit in the tubular extension 20 by means of a hole 21 formed in the bottom of the cup. The neck 20 is preferably threaded and screws in a threaded hole in the wall of the manifold.

I prefer to provide the cup 2 with a removable cap, as 3, and also to have this cap provided with a cavity or recess 30, in its upper surface. This cap is also provided with a hole which is in alignment with the hole 21 in the bottom of the cup.

A tube 4, which is of copper or other ductile metal, which can be bent and caused to extend in any direction desired, is provided of a size to snugly fill the hole in the cap 30. This is provided with a tip 40 which is fixedly secured thereto and which is of a size and length to snugly fill the hole in the bottom of the cup. This tube is fixed in place so that it may be easily withdrawn and easily inserted. Using an extension 40 of smaller diameter somewhat facilitates entering the tube so that its inner end enters and closes the opening at the bottom of the cup. When it is in place it cuts out communication between the chamber of the cup 2 and the discharge neck or tube 20.

The tube 4 extends from the cup 2 to a point where its other end connects with the radiator 5, preferably at a point above the water level therein, as for instance, with the neck of the filling opening 50. In its intermediate parts, as 41, it is coiled about or otherwise brought in close connection with the parts of the engine cylinders, so that it will become heated therefrom. The watery vapor which is given off by the water in the radiator will be drawn through tube 4 into the intake manifold 1, and will be highly heated by radiation from the engine cylinders.

I have provided a tip through which this vapor is discharged into the manifold, the same consisting of a perforated tube 6, which fits within the end of the tubular discharge stem 20, and which projects into the manifold. The perforations in this tip are small and extend all about the same. The inner end of this tip is closed. In consequence, the watery vapor discharged through this tip is discharged in all directions and mixes thoroughly with the combustion charge. It therefore adds a sufficient amount

of aqueous vapor to the charge to cause smoother and better running and also to prevent the deposit of carbon.

If at any time it becomes desirable to supply a few priming charges to the engine, this may readily be done by withdrawing the tube 4. With this comes the tip 40 and the cup 2 is then in free communication with the discharge tip 6. To close this off or control the area of this communication as may be desired, I prefer to employ a valve which is located between the cup and the discharge tip 6.

In Fig. 2 this consists of a set screw 7 which, when screwed in, closes the communicating channel. The cup 2, when the tube 4 is withdrawn, may be filled with gasolene. The quantity which it holds will be sufficient for a number of charges for the engine. This gasolene will be discharged through the tip 6 and will enrich the charge for a short time. Once the engine has been properly started, the tube 4 may be reinserted. As this may be very conveniently done the trouble required for priming the engine is very slight.

The device as shown in Fig. 2 is a device made especially for this purpose. The device as shown in Fig. 3 is one made from stock parts. It employs a nipple 8, as the laterally extending stem, which is secured to the manifold, a set screw 70, which screws into the side of this nipple, an elbow 80, and an ordinary oil cup 81.

What I claim as my invention is:

1. A vapor feed and priming attachment for internal combustion engines comprising a cup having a tubular discharge neck extending laterally from its bottom and adapted to be connected with the intake manifold of the engine, the cover of the cup and its bottom having aligned holes, the one in its bottom constituting the connection with the tubular discharge neck, and a vapor supply tube extending from the radiator above the water level and adapted to have one end removably inserted through the hole in the cover and to enter the hole in the bottom of

the cup, to thereby permit the cup to be used as a priming cup when the vapor supply tube is removed.

2. A vapor feed and priming attachment for internal combustion engines comprising a cup having a tubular discharge neck extending laterally from its bottom and adapted to be connected with the intake manifold of the engine, the cover of the cup and its bottom having aligned holes, the one in its bottom constituting the connection with the tubular discharge neck, and a vapor supply tube extending from the radiator above the water level and adapted to have its other end removably inserted through the hole in said cover and into the hole in the bottom of the cup, whereby the cup may be used as a priming cup by removing said tube, and means for closing the tubular discharge neck between the cup and the manifold.

3. A vapor feed and priming attachment for internal combustion engines comprising a cup having a tubular discharge stem adapted to be connected with the intake manifold and connecting with the cup by a hole in the bottom thereof, a valve adapted to close said stem, a cover for the cup having a hole aligned with the hole in the bottom of the cup, and a vapor supply tube adapted to be inserted through the hole in the cover and to enter the hole in the bottom of the cup.

4. A vapor feed and priming attachment for internal combustion engines comprising a cup having a tubular discharge stem adapted to be connected with the intake manifold and connecting with the cup by a hole in the bottom thereof, a valve adapted to close said stem, a perforated tubular tip carried by said stem and adapted to project into the manifold, a cover for the cup having a hole aligned with the hole in the bottom of the cup, and a vapor supply tube adapted to be inserted through the hole in the cover and to enter the hole in the bottom of the cup.

Signed at Seattle, Washington, this 9th day of October, 1918.

ARCHIBALD ROBERTSON.
